UNITED STATES PATENT OFFICE.

CHARLES B. YOUNG, OF AURORA, AND GARTH G. GILPIN, OF RIVERSIDE, ILLINOIS.

VESTIBULE-DIAPHRAGM FOR RAILWAY-CARS.

1,186,963.

Specification of Letters Patent. Patented June 13, 1916.

Application filed June 12, 1914. Serial No. 844,638.

To all whom it may concern:

Be it known that we, CHARLES B. YOUNG and GARTH G. GILPIN, citizens of the United States, residing at Aurora, in the county of Kane and State of Illinois, and Riverside, in the county of Cook and State of Illinois, respectively, have invented a certain new and useful Improvement in Vestibule-Diaphragms for Railway-Cars, of which the following is a full, clear, concise, and exact description, reference being had to the accompanying drawings, forming a part of this specification.

Our invention relates to improvements in vestibule diaphragms for railway cars.

One of the main objections to the present form of vestibule diaphragms used on railway cars lies in the fact that the same are not fireproof, since the same are generally made of canvas or like inflammable material, and often get on fire caused by sparks from the locomotive. These fires sometimes spread to the car, and, in any event, require considerable time and labor to extinguish the same to prevent spreading.

One of the objects of our invention is, to provide a flexible diaphragm for railway cars which is absolutely fireproof.

Other objects of our invention are, to provide a vestibule diaphragm of durable construction, and yet which may be manufactured at relatively small expense.

Other objects of our invention will more fully appear from the description hereinafter given.

In the drawings forming a part of this specification, Figure 1 is an end elevation of a car vestibule and diaphragm showing our improvements in connection therewith. Fig. 2 is a side elevation of the structure shown in Fig. 1. Fig. 3 is an enlarged vertical sectional view taken substantially on line 3—3 of Fig. 1, parts being broken away to prevent crowding of the drawing. Fig. 4 is a horizontal sectional view taken substantially on line 4—4 of Fig. 1, upon an enlarged scale. Fig. 5 is a vertical sectional view taken through the top of the vestibule diaphragm, and showing the position of the parts when the same are compressed or telescoped. Fig. 6 is a sectional view of the upper portion of a diaphragm and plates to which it is attached, showing another form of our improvements. Figs. 7 and 8 are

views similar to Fig. 6, showing other forms 55 of our improvements.

Referring now to Figs. 1 to 5 inclusive, 10 denotes the vestibule diaphragm face plate, which is secured to the buffer plate 11 at the bottom thereof in the usual manner. 60 Mounted on the buffer plate 11 is the foot plate 12, which slides under the vestibule floor plate 13. The buffer plate 11 is normally pressed outwardly by the usual buffer mechanism (not shown) by means of the 65 buffer stems 14. 15 denotes the end plate secured to the end of the vestibule, said plate having mounted thereon brackets 16—16, in which slidably engage the ends of a plurality of bowed springs 17, which pass 70 through and are secured to another bracket 18 firmly attached to the upper cross member of the face plate 10. As will be understood, the springs 17 normally tend to press the upper portion of the face plate and the 75 diaphragm carried thereby, outwardly in the usual manner.

Our improved diaphragm, as shown in Figs. 1 to 5 inclusive, comprises a plurality of relatively slidably mounted, telescoped 80 sheet metal members, of which those referenced 19 and 20 are secured to the end plate 15 of the vestibule; 21 is secured to the diaphragm face plate 10; and 22 and 23 are secured to each other, and slidably 85 mounted between the members 19 and 20, as shown most clearly in Figs. 3 and 4. As will be understood, each of the members 19 to 23, inclusive, is substantially of inverted U-shape, that is, each member has 90 two vertical legs located on the opposite sides of the vestibule, and a top cross portion, and all of which are preferably rounded at the upper corners, as indicated by the reference 24 in Fig. 1. Each of the members 19, 21 and 22 is substantially of Z-shape in cross section. The flange 25 of the member 19 is secured to the plate 15 by rivets or other suitable means, and the flange 26 of the member 21 is also suitably 100 secured to the face plate 10 by rivets or bolts, as shown. The flange 27 on the opposite end of the member 19 on which the flange 25 is located is turned inwardly and is adapted to limit the outward movement 105 of the member 22 by engagement with the flange 28 of the latter. Similarly, the flange 29 on the inner edge of the member

21 engages with the flange 30 on the outer edge of the member 22, to thereby pull the latter outwardly, and also to limit the outward movement of the sheet metal member

5 21. The member 20 on its inner edge is provided with an inturned flange 31, which is secured to the end plate 15 by any suitable means, and the outer edge of the member 20 is preferably flared as indicated at 10 32. The member 23 is provided with an outwardly extending flange 33, which is secured to the flange 28 of the member 22 by any suitable means such, for instance, as spot welding; and the outer edge of the 15 member 23 is also flared as indicated at 34. As will be understood, all the flanges on the edges of the members 19 to 23, inclusive, extend along the sides, corners and tops thereof.

20 From the preceding description, it is thought that the operation will be evident, it being apparent that the member 21 telescopes within the members 22 and 23, and the latter in turn telescopes within the 25 members 19 and 20. All these sheet metal members are of relatively light material and flexible, thereby adapting the diaphragm to yield laterally and vertically to accommodate itself to all the movements incident 30 to the operation of the cars on which they are used. Furthermore, the parts are so designed that all the members of the diaphragm proper are in yielding frictional engagement with each other, which is an 35 important consideration in preventing rattling of the parts. The parts are of simple construction, the same may be cheaply manufactured, and provide an absolutely fire-proof vestibule. In addition to the foregoing, it is apparent that the inner surfaces 40 of the diaphragm proper are substantially flat, which is an improvement over the plaited form of diaphragm now commonly used, since with the latter construction 45 there are numerous recesses or grooves in which a passenger passing through the vestibule may get his hands caught upon sudden compression of the diaphragm.

Referring now to Fig. 6, the form shown 50 therein comprises members 119, 120, 122, and 121, of which those referenced 119 and 120 are suitably secured to the end plate of the vestibule, and the member 121 is bolted or otherwise secured to the diaphragm face 55 plate 110. The member 120 corresponds substantially to the member previously described and referenced 20, but the member 119 instead of being provided with a right-angled flange, is provided with a hook 127 60 with which is adapted to coöperate and engage an oppositely turned hook 128 on the inner edge of the member 122. The outer edge of the member 122 is provided with a curved hook flange 130, and is adapted to 65 engage with an oppositely turned curved

flange 129 on the member 121. The diaphragm face plate is mounted in the usual manner, and is pressed outwardly at the top by means of leaf springs 117.

In the arrangement just described, it will 70 be seen that the intermediate metallic member is formed of a single piece, and telescopes between the members 119 and 120. As will be understood, the intermediate member 122 will be prevented from becoming displaced laterally on account of the fact that any tendency for said member to move to one side will be resisted by the engagement of the leg thereof on the opposite side with the adjacent legs of the members 75 119, 120 and 121. The same result occurs when the intermediate member 122 tends to move upwardly or downwardly relatively to the other members of the diaphragm with which it coöperates.

In Fig. 7, the diaphragm shown therein comprises metallic plates or strips 219, 220, 222 and 221. As shown, the members 219 and 220 are secured by rivets or other suitable means to the vestibule end plate 215, the member 219 being provided with a right-angled flange 225, the member 220 with a similar flange 231. Pin and slot connections are provided between the members 222 and 219, one of which is indicated at 235, it being understood that these pin and slot connections will be disposed at suitable distances apart along each leg and across the top of the diaphragm members, the slots being formed in the plate 219 and the pin attached to the member 222, so that the outward movement of the latter will be limited in a well known manner. The outer edge of the sheet metal plate 222 is provided with an in-turned curved flange 230 adapted to engage and coöperate with an oppositely turned curved flange 229 on the inner edge 95 of the member 221, the latter being secured to the face plate 220 in any desired manner.

Referring to Fig. 8, the construction shown therein employs only three sheet metal members, the same being referenced, respectively, 319, 322 and 321, the latter being attached to the face plate 320 by bolts, as shown. The member 319 is secured to the end plate of the vestibule in the same manner that the previously described members 19, 119 and 219 are secured. The intermediate member 322 is substantially Z-shaped in cross section throughout its length, the flange 328 on the inner edge thereof being turned inwardly, and the flange 330 on the outer edge thereof being extended outwardly. A plurality of pin and slot connections 335 and 336 are provided between the members 321 and 322, and 322 and 319, respectively, said pin and slot connections being disposed throughout the length of the members as above described in connection with the structure shown in Fig. 7. 100 105 110 115 120 125 130

When the diaphragm shown in Fig. 8 is collapsed, the inner edge of the plate 321 will engage the flange 328, and move the intermediate plate inwardly, and likewise the outer edge of the plate 319 will engage the flange 330 to slide the latter over the plate 321.

All of the constructions hereinbefore described provide sufficient movement or telescopic action when the face plate is moved inwardly toward the end of the vestibule, and, furthermore, all the same are not only fireproof, but are so arranged that they are adapted to shed water, snow, or the like, without danger of the same getting inside of the vestibule.

We have herein shown and described several forms of our invention, but it will be understood that the invention may be embodied in different constructions than those herein shown; for instance, various other structural shapes than those herein shown may be employed without departing from the spirit of the invention.

We claim:—

1. In a car construction, in combination, a vestibule end plate, a diaphragm face plate, a pair of metallic members secured to the vestibule end plate, said members being spaced apart, a metallic member secured to the face plate, and an intermediate member slidably mounted with respect to said other members, and movable in and out between said pair of members attached to the end plate.

2. A fireproof flexible diaphragm for railway cars comprising a pair of spaced sheet metal members arranged to be attached to the end plate of a vestibule, a sheet metal member slidably mounted between said pair of members, a sheet metal plate arranged to be attached to a vestibule diaphragm face plate, said members being provided with flanged edges adapted to limit the outward movement thereof.

3. In a car construction, in combination, a vestibule end plate, a diaphragm face plate, and a diaphragm mounted between and carried by said plates, said diaphragm comprising a pair of spaced members attached to the end plate, a pair of members rigidly secured together and slidably mounted between said first named pair of plates, and a third plate attached to the diaphragm face plate, and slidably mounted between said second named pair of plates.

4. In a car construction, in combination, a vestibule end plate, a diaphragm face plate, and a diaphragm mounted between and carried by said plates, said diaphragm comprising a pair of spaced members attached to the end plate, a pair of members rigidly secured together and slidably mounted between said first named pair of plates, and a third plate attached to the diaphragm

face plate, and slidably mounted between said second named pair of plates, said members being provided with flanged edges adapted to limit the outward movement thereof.

70

5. A vestibule diaphragm for railway cars comprising, a plurality of telescoped metallic members, each of said members having laterally extending flanges at their edges, the flanges nearest the car end, of each of said members all extending in one direction, and all the flanges of said members farthest away from the car end, extending in the opposite direction.

75

6. A vestibule diaphragm for cars comprising a plurality of sheet metal members telescopically arranged, one of said members being adapted to be secured to a car end and another of said members being adapted to be secured to a vestibule diaphragm face plate, each of said members on the edge nearest the car end having an outwardly extending flange, each of said members also having an inwardly turned flange on its edge nearest the diaphragm face plate, some of said flanges overlapping.

80

7. A vestibule diaphragm for a railway car comprising a plurality of telescopically arranged diaphragm members carried entirely by the car, the inner faces of said members extending in parallel planes offset from each other only by substantially the thickness of the sheet metal forming said members, each of said members having integral sides and top portions to thereby maintain the passageway inclosed by the diaphragm of substantially the same width throughout.

95

8. The combination with a car having a movably mounted diaphragm face plate, of a metallic diaphragm side member carried by said face plate, a metallic diaphragm side member carried by the car, and a third diaphragm side member bridging the space between and overlapping said first two named diaphragm side members, said first two named side members being normally separated longitudinally of the car.

100

9. A vestibule diaphragm for cars having a movably mounted diaphragm face plate, comprising more than two diaphragm side members telescopically arranged and connected to the car end and face plate, the outer face of each succeeding member being arranged in a different plane from and outside of the preceding member as viewed lengthwise of the car, said members being provided with overlapping marginal portions having flanges to prevent separation thereof.

105

10. A vestibule diaphragm for railway cars comprising at least three telescoped sheet metal diaphragm members each having sides and a top portion, the end ones of said three members being adapted to be each

110

115

120

125

130

fixedly attached to the end of a car and a diaphragm face plate respectively, relative de-wise movement between the diaphragm face plate and the car end being accommodated entirely by said members and between the respective points of attachment to the car end and face plate.

11. A vestibule diaphragm for cars comprising three telescoped diaphragm members, two of said members being each double walled and one slidale within the other, to thereby permit a contraction of the space between the car and diaphragm face plate to a distance substantially equal to the width 10 of one of said members.

12. A vestibule diaphragm for a passenger car comprising a plurality of metallic side members telescopically arranged to permit

a contraction of the space between the car end and the diaphragm face plate to a distance substantially equal to the width of one of said member, said members being carried entirely by the car and the inner surfaces of the sides of the diaphragm formed by said members being substantially flat to thereby avoid recesses and prevent injury to passengers passing through the vestibule during sudden operation of the diaphragm, said members being inherently flexible laterally to accommodate the movements of the 20 diaphragm face plate.
